STILE CLAMP

William C. Wildman, 3915 Hoover St.,
Boise, Idaho 83705

Filed Apr. 5, 1971, Ser. No. 131,583

Term of patent 14 years

Int. Cl. D8—05

U.S. Cl. D8—72

FIG. 1 is a right front perspective view of the stile clamp embodying my new design.

FIG. 2 is a left rear perspective view as viewed from the bottom.

I claim:

The ornamental design for a stile clamp, substantially as shown.
